ATTYS.

UNITED STATES PATENT OFFICE.

OSCAR C. DAVIS, OF BROCKTON, MASSACHUSETTS.

PIECED OUTER-SOLE.

1,239,361.

Specification of Letters Patent.

Patented Sept. 4, 1917.

Application filed November 22, 1916. Serial No. 132,787.

To all whom it may concern:

Be it known that I, OSCAR C. DAVIS, a citizen of the United States, residing at Brockton, in the county of Plymouth and State of Massachusetts, have invented new and useful Improvements in Pieced Outer-Soles, of which the following is a specification.

This invention relates to a full length pieced outer sole, and it has for its object to provide an outer sole of improved construction, whereby its cost is reduced and other desirable results are attained.

The invention consists in the improvements which I will now proceed to describe and claim:

Of the accompanying drawings forming a part of this specification,—

Figure 1 represents a bottom view of a shoe including an outer sole embodying my invention, a portion of the veneer piece hereinafter referred to being broken away.

Fig. 2 represents a side view of the shoe, a portion of the bottom thereof being shown in section on the line 2—2 of Fig. 1.

Fig. 3 represents a fragmentary sectional view showing the invention somewhat differently embodied.

The same reference characters indicate the same or similar parts in all of the views.

My improved outer sole may be embodied in a shoe, the upper, outer sole and inner sole of which are assembled and connected in any suitable manner.

My improved outer sole, as shown by Figs. 1 and 2, is composed of three parts or pieces, namely, a relatively thick tap piece 12, a relatively thick shank and heel-seat piece 13, said pieces meeting to form a transverse joint extending across the sole from edge to edge, and a relatively thin sole-shaped veneer piece 14, including integral fore and shank portions forming the entire exposed bottom surface of the sole.

Each of said pieces 12 and 13 has an end face of greater width than the thickness of the sole. In the embodiment of the invention shown by Figs. 1 and 2, the end face of the piece 12 is indicated by 12^a, while the end face of the piece 13 is indicated by 13^a, each of said faces being of the angular form shown by Fig. 2, and formed by cutting away some of the material of each piece.

In the embodiment of the invention shown by Fig. 3, the end faces 12^b and 13^b are inclined relatively to the sides of the sole, and

are formed by beveling or scarfing the pieces 12 and 13.

The pieces having the described complementary end faces are united by abutting said faces together after they have been coated with a suitable cement, although, if desired, the reduced end portions may be united by metallic fastenings, or by stitches passed through the reduced portions and used either with or without cement.

The veneer piece 14 is formed to cover the under sides of the pieces 12 and 13, and extend across the joint formed by the meeting ends of the said pieces. Said veneer piece is preferably a relatively thin skiving removed from the grain side of a sheet of sole leather and applied to the pieces 12 and 13 with the grain side outward. The veneer piece 14 is attached by cement to the pieces 12 and 13.

The joint formed by the meeting ends of the pieces 12 and 13, and the portion of the veneer piece covering said joint are so located that they are wholly raised above the wear-sustaining portion of the outer sole, as indicated by Fig. 2, and as indicated approximately by the dotted line a—a in Fig. 1, said line denoting the rear edge of the area of the bottom of the forepart of the sole which is subjected to wear by contact with the ground.

When the shoe is subjected to wear, the fore portion of the veneer piece sustains wear to a limited extent, and when said portion is worn through, the piece 12 is exposed and sustains further wear. A portion of the veneer which is not subjected to wear permanently covers and reinforces the joint formed by the meeting ends of the pieces 12 and 13, and is not affected by the wearing away of the fore portion.

The pieces 12 and 13 form a relatively thick pieced sole body. If desired, the veneer piece 14 may be secured to said sole body by a layer 16, applied as a coating to the outer sides of said pieces, and composed of a plastic, adhesive mixture, which may include any suitable cement and granular wear-resisting material such as powdered carborundum. The veneer piece 14 is applied to the outer side of the layer 16 while the latter is in a plastic and adhesive condition. When the layer 16 is hardened by drying it adheres firmly to the pieces 12 and 13 and to the veneer piece 14, the fore portions of said veneer pieces and layer successively

sustaining wear on the shoe bottom. The layer 16 therefore constitutes a fourth piece of the sole.

One advantage resulting from the described construction is that the tap piece 12 may be made of a material such as chrome leather, which, although relatively expensive, is well adapted to resist wear, the piece 13 being made of a less expensive material, 10 the relatively small cost of which compensates for the cost of the tap piece.

I claim:

1. A pieced outer sole comprising a relatively thin sole-shaped veneer piece, including integral fore and shank portions forming the entire exposed bottom surface of the sole, a relatively thick tap piece, and a relatively thick shank piece cemented to said veneer piece and having complementary meeting end faces, united to form a joint which is covered by a portion of said veneer piece, said joint and joint-covering portion being located wholly in a raised portion of the sole which is above the acting tread face thereof.

and is not exposed to wear, said veneer constituting a continuous uninterrupted sole face, the fore portion of which is adapted to sustain wear to a limited extent, the said joint-covering portion of said veneer permanently covering and reinforcing said joint.

2. A pieced outer sole comprising a relatively thin sole-shaped veneer piece including integral fore and shank portions forming the entire exposed bottom surface of the sole, a relatively thick pieced sole body composed of a tap piece and a shank piece, said tap and shank pieces having complementary meeting end faces united to form a joint located wholly in a raised portion of the sole which is above the acting tread face thereof, 40 and a layer composed of an adhesive mixture interposed between and uniting the said veneer piece and said pieced sole body, and adapted to sustain wear after the fore portion of the veneer has been worn way.

In testimony whereof I have affixed my signature.

OSCAR C. DAVIS.
